ELECTRIC VACUUM CLEANER

Murray G. Wachsman, Forest Hills, N.Y., assignor to
Shop-Vac Corporation, Wood-Ridge, N.J.

Filed May 23, 1972, Ser. No. 256,203

Term of patent 14 years

Int. Cl. D15—05

U.S. Cl. D7—166

FIG. 2.FIG. 1.FIG. 1 is a side elevation view of an electric vacuum cleaner in accordance with the present design, with the peripheral annular flange around the top of the can being partially cut away, it being understood that the view from each direction of the top portion of the cleaner above the can would be identical; and

FIG. 2 is a top plan view of the electric vacuum cleaner in accordance with the present design.

I claim:

The ornamental design for an electric vacuum cleaner, as shown and described.
